BRUSH

Filed May 20, 1926

Inventor
Fern A. Skinner

By Watson E. Coleman
Attorney

UNITED STATES PATENT OFFICE.

FERN A. SKINNER, OF MOUNTAIN VIEW, CALIFORNIA.

BRUSH.

Application filed May 20, 1926. Serial No. 110,555.

This invention relates to brushes and more particularly to a device of this character so constructed that it may be cheaply produced and will be durable and efficient in service.

5 A further object of the invention is to provide a device of this character wherein the bristle elements are removable, so that they may be very readily cleansed.

10 A further object of the invention is to provide a construction enabling the use of a spiral bristle clump in a brush of this character.

15 These and other objects I attain by the construction shown in the accompanying drawing, wherein for the purpose of illustration is shown a preferred embodiment of my invention and wherein:—

Figure 1 is a plan view of a brush constructed in accordance with my invention;

20 Figure 2 is an end elevation thereof;

Figure 3 is a transverse sectional view therethrough;

Figure 4 is a section on the line 4—4 of Figure 2;

25 Figure 5 is a plan view of the bristle receiving face of the back.

Referring now more particularly to the drawings, the brush includes a back 10, the bristle receiving face of which is formed 30 with longitudinally extending concave grooves 11 having their adjacent edges spaced. The ends of the back 10 at the centers thereof at a point intermediate the grooves 11 have formed therein sockets 12 and the bristle receiving face of the brush is notched to form coves 13 extending from the sockets 12 to the bristle receiving wall. The bristle elements are formed by employing two wires 14 and 15 or a single wire 35 bent medially between which are inserted bristles 16 after which the wire core is twisted to provide a spirally arranged bristle clump of circular formation.

The bristle clump terminates at points 40 spaced from the ends of the wires and these ends are reverted in spaced relation to the clumps to provide inwardly directed terminals 17 for engagement in the sockets 12 and

connecting portions 18 which will engage in the coves 13 and prevent movement of the 50 bristle clumps by maintaining them firmly in engagement in the grooves 11. The wire employed is resilient and the ends of the inwardly directed portions 17 are spaced apart a distance less than the distance between 55 adjacent ends of the coves 13, so that the terminal portions 17 may not escape from the sockets 12 which are of even greater depth than the coves.

By this structure, a brush having very 60 rigid bristles can be produced and the bristle clumps may be readily removed at any time for cleansing. The brush clumps may be reversed as to the grooves which they occupy and in so doing they are longitudinally reversed, with the result that the sides of the clumps which were originally in engagement with one another are arranged at the outside of the brush, providing a fresh surface at this point. 70

Since the construction hereinbefore set forth is obviously capable of a certain range of change and modification without materially departing from the spirit of the invention, I do not limit myself to such specific 75 structure except as hereinafter claimed.

I claim:—

In a brush, a back having spaced longitudinally extending grooves formed in its bristle receiving face, the ends of the back 80 having sockets and bristle holders each having a twisted metallic core arranged within said grooves, the ends of the metallic cores of said holders being provided with reverts for engagement in the sockets, said sockets being disposed at the centers of the ends of the back and each receiving the corresponding reverts of the cores of said bristle holders, the end wall of the back having notches connecting said sockets with the 85 bristle receiving face of the back and adapted to receive the connection between the reverts of the cores and the body thereof. 90

In testimony whereof I hereunto affix my signature.

FERN A. SKINNER.
